UNITED STATES PATENT OFFICE.

EUGENE KIBELE, OF CHATTANOOGA, TENNESSEE, ASSIGNOR TO SOUTHERN WELL WORKS COMPANY, OF CHATTANOOGA, TENNESSEE, A CORPORATION OF TEXAS.

LIFTING-CLAMP FOR WELL-CASINGS.

1,231,616.

Specification of Letters Patent.

Patented July 3, 1917.

Application filed April 17, 1914, Serial No. 832,531. Renewed April 9, 1917. Serial No. 160,889.

To all whom it may concern:

Be it known that I, EUGENE KIBELE, a citizen of the United States, residing at Chattanooga, in the county of Hamilton and

5 State of Tennessee, have invented certain new and useful Improvements in Lifting-Clamps for Well-Casings; and I do declare the following to be a full, clear, and exact description of the invention, such as will 10 enable others skilled in the art to which it appertains to make and use the same, reference being had to the accompanying drawings, and to the letters and figures of reference marked thereon, which form a part of 15 this specification.

My invention relates to new and useful improvements in lifting clamps or elevators for well-casings, pipes, drill rods and other like objects, its primary object being the 20 provision of a lifting clamp or elevator which may be readily applied to, or removed from the casing section or other object to be lifted.

I accomplish the above object by constructing a clamp including hingedly connected parts, or sections, having coacting handles one of which carries a swinging latch and the other a keeper adapted to readily receive the latch when the handles 30 are swung together to close the clamp.

In this connection a further object of my invention is to so construct the handles of the clamp sections that their grip portions, that is the parts grasped by the operator 35 in manipulating the clamp, will be spaced even when the clamp is closed thereby preventing pinching or jamming of the operator's fingers when applying the clamp.

A further object which I have in view is 40 to mount or form the latch and its keeper on the handles in such a manner both with respect to each other and the handles that, when the clamp is closed and fastened, the mere grasping of the handles, in a natural 45 manner, to open the clamp will free the latch from its keeper and consequently release the clamp sections.

This same relative arrangement of parts results in distribution of strain to the latch 50 and its keeper and to the parts of the clamp when the latter is in use.

A yet further object which I have in view is the provision of grab hook receiving bails 55 swingingly carried one by each clamp section in such a way that they may be brought

together above the object engaged by the clamp to receive a single hook and so prevent swinging or tilting of such object while it is being raised.

With these and other objects in view, my invention will be more fully described, illustrated in the accompanying drawings which disclose a preferred embodiment of my lifting clamp and then specifically pointed out in the claims which are attached to and form a part of this application.

In the drawings, in which similar reference numerals designate corresponding parts throughout the several views:

Figure 1 is a perspective view of my clamp applied to a section of well casing;

Fig. 2 is a top plan view of the clamp in closed position;

Fig. 3 is a side elevation of the clamp;

Fig. 4 is a front elevation of the clamp closed;

Fig. 5 is a perspective view of the clamp in open position.

My invention primarily includes coacting clamp sections 10 and 11 connected at one end by a hinge pin 12 and provided at their free ends with radially extending handles 13 and 14 one of which carries a latch 15 while the other carries a latch keeper 16. Bails 17 are provided as an attaching means 85 for a block and tackle or other mechanism employed to lift the clamp and object which it engages. The entire clamp is, of course, formed of metal, preferably steel, each section, with its handle, being cast or otherwise formed in a single piece, the body portions of the two sections, when the clamp is in use, forming in effect, a tubular band or sleeve in which the casing section to be raised is clamped.

More specifically the body portions of the clamp are formed at one end with interengaging hinge ears or lugs 18 having alined bores to receive the pivot pin 12 the ends of which are headed to prevent its disengagement, its heads seating in recesses formed in the outer faces of the upper and lower ears to lie flush with the surface. The ears are formed in such a manner as to limit the swinging of the sections away from each other for convenience when applying the clamp and offset to space the adjacent edges of inner faces of the clamp sections when they are swung together to permit tight closing.

The handles 13 and 14, as previously described extend from the free ends or edges of the body portions of the clamp sections in a radial direction, being consequently located diametrically opposite the hinge pin 12. These handles may taper in thickness toward their outer ends but in any event their inner faces are plain and smooth surfaced to bear evenly together when the clamp is in use. One of the handles, in the present instance the handle 14, is provided intermediate its height and adjacent its clamp section with a slot 19 the side faces of which are curved concentrically with respect to the hinge pin 12. The other handle carries the keeper 16 which is longitudinally curved in the same manner to pass freely through the slot 19 upon swinging of the clamp sections toward or away from each other. This keeper is generally cast integrally with the handle and is so proportioned that when the clamp is closed it will project considerably beyond the handle 14. The keeper is provided in its upper edge with a square shouldered notch 20 the sides of which are parallel to the outer face of the handle 14 when the clamp is closed, the inner face of the notch then lying in the plane of the said handle face. Beyond this notch the upper edge of the keeper is inclined to provide a latch engaging cam face over which the latch 15 will ride to seat in the notch 20. A rivet 21, or other suitable pivot swingingly supports the latch 15 which consists of a substantially rectangular plate the free end of which is proportioned to seat in the notch 20. The swinging of this latch is limited by vertically spaced pins or stop lugs 22 and 23 either cast integrally with or otherwise secured to the handle 14. The upper lug or pin 22 merely prevents unnecessary upward movement of the latch upon unfastening the clamp while the pin 23 supports the latch, when the clamp is open, in position to be engaged by the inclined face of the keeper as the clamp is closed thus causing the latch to ride over the keeper to automatically seat in the notch 20 and lock the clamp when the latter is closed. The inner face of the handle 14 is, of course, recessed to seat the over struck end of the rivet 21 so that the handles may closely engage each other. In order to produce a ready and in fact practically automatic means for releasing the latch the handles 13 and 14 have their lower edges cut away intermediate their length to provide registering finger-receiving openings 24. Upon grasping the free ends of the handles, one in each hand, to open the clamp, the fingers of the right hand enter the opening 24 of the handle 14 and engage the lower edge of the latch 15 so that upon gripping the handles the latch

is raised and freed from the keeper. To facilitate such grasping of the handles their lower free end portions are flared or curved away from each other to provide grip 25 which, even when the clamp is closed are spaced sufficiently to permit the fingers of both hands to be inserted between them. This construction also renders it impossible for the operator to pinch or jam his fingers between the handles when opening or closing the clamp. The lower edges of the grips 25 are preferably inturned or thickened interiorly to provide shoulders 26 which prevent the handles from slipping out of the operator's hands.

The clamp sections are provided intermediate their hinge ends and handles with vertically disposed radially projecting eyes 27 diametrically located, when the clamp is closed, and preferably cast integrally with their respective clamp sections. These eyes receive the bails 17 as clearly shown in the drawings. Each bail is in the form of an elongated, closed ring wider at its upper than at its lower end and with its upper end curved inwardly so that when the bails are swung up and bear against the outer faces of the clamp their upper ends will stand in relatively close relation to each other. Because of this a single grab hood 28 carried by the cable 29 of a block and tackle or other lifting mechanism, not shown, may be passed through both bails thereby distributing the strain equally upon both clamp sections and preventing swinging or tilting of the clamp and supported casing section or pipe. The upper portions of the bails are preferably thickened to strengthen them and to provide flat faces 30 which engage each other under strain upon the bails, resulting in added steadiness.

To raise a casing section, pipe or other object the clamp in open position is brought into engagement with the object to be raised and the handles then swung together to close the clamp about the object, the latch positively holding the clamp when it is closed, as previously explained. This may be done while the clamp is suspended from the hoisting cable 29, if not previously. The clamp may be removed by grasping the handles and swinging the sections apart, the grasping of the handles releasing the latch in the manner described.

From the above description it will be apparent that my improved lifting clamp is simple in construction, durable and convenient in operation. It will of course be understood that various changes in size, shape and proportion found desirable by circumstances may be made. In fact I do not wish in any way to limit myself to the specific details illustrated and described as any minor changes in detail, within the scope of the appended claims, may be made when

ever desired without in any way departing from the spirit of my invention.

Having thus described my invention, what I claim as new is:

- 5 1. A lifting clamp or elevator for well casings including coacting clamp sections hinged at one end to swing toward and away from each other, handles carried by the free ends of the sections, and a gravity
- 10 latch for securing the handles together, one of the handles being formed with an opening in its lower portion beneath the latch to permit the latch to be released by the hand in grasping the handle.
- 15 2. A lifting clamp or elevator for well casings including coacting clamp sections hinged at one end, handles carried by the free ends of the sections engaging each other when the sections are swung together,
- 20 20 and coacting latch and keeper members carried by the handles, one handle having a finger receiving opening over which the latch extends.
- 25 3. A lifting clamp or elevator for well casings including coacting clamp sections

hinged at one end, handles carried by their free ends, and means for positively holding the handles together, the free ends of the handles at adjacent edges having downwardly extending spaced members to serve 30 as hand grips in opening and closing the clamp.

4. A lifting clamp or elevator for well casings including swingingly connected clamp sections having radially extending handles at their free ends, said handles having at their outer ends downwardly and outwardly spaced hand grips, the lower portion of the handles back of said grips being formed with openings to receive a 40 portion of the hand in grasping the grips, and a keeper and latch for holding the handles together.

In testimony whereof I affix my signature in presence of two witnesses.

EUGENE KIBELE.
